US0D1008289S

(12) **United States Design Patent** (10) Patent No.: **US D1,008,289 S**
 Yazdansepas et al. (45) Date of Patent: ** Dec. 19, 2023

(54) **HUMAN MACHINE INTERFACE DISPLAY SCREEN OR PORTION THEREOF WITH GRAPHICAL USER INTERFACE FOR INDUSTRIAL APPLICATIONS**

(71) Applicant: **Hitachi Global Air Power US, LLC**, Michigan City, IN (US)

(72) Inventors: **Iman Yazdansepas**, Westville, IN (US); **Arvind Rajavelu Giri**, Michigan City, IN (US); **Sankara Yadavalli**, Palatine, IL (US)

(73) Assignee: **HITACHI GLOBAL AIR POWER US, LLC**, Michigan City, IN (US)

(**) Term: **15 Years**

(21) Appl. No.: **29/805,629**

(22) Filed: **Aug. 27, 2021**

(51) LOC (14) Cl. **14-04**

(52) U.S. Cl.

USPC **D14/485**

(57) **CLAIM**

The ornamental design for a human machine interface display screen or portion thereof with graphical user interface for industrial applications, as shown and described.

DESCRIPTION

The single FIGURE shows a front view of a human machine interface display screen or portion thereof with graphical user interface for industrial applications showing our new design.

The broken line showing of the human machine interface display screen or portion thereof is for illustrative purposes and forms no part of the claimed design.
